DESIGN FOR A WATCH BRACELET

Ardé Bulova, New York, N. Y.

Application July 15, 1935, Serial No. 57,631

Term of patent 3½ years

To all whom it may concern:

Be it known that I, Ardé Bulova, a citizen of the United States, residing in New York city, in the county of New York and State of New York, have invented a new, original, and ornamental Design for a Watch Bracelet, as shown, of which the following is a specification, reference being had to the accompanying drawing, forming part thereof.

I claim:

The ornamental design for a watch bracelet, as shown.

ARDÉ BULOVA.
